ABSTRACT

A turbo molecular pump is provided with rotor and stator wheels containing thin-walled blades each having the same thickness, with the blades extending radially outwardly from a carrier body which can be either ring or disc shaped. Each blade is shaped so that the acute angle formed between the tangential plane at any given point on its surface spaced from the axis of the wheel and the plane of the wheel decreases as the distance of the point increases from the axis of the wheel.

ROTOR AND STATOR WHEEL CONSTRUCTION FOR A TURBO MOLECULAR PUMP

The present invention is directed to turbo molecular pumps and, more particularly, it concerns the shape or configuration of blades used in the rotor and stator wheels in such pumps.

Turbo molecular pumps are known which include a plurality of rotor wheels arranged to rotate quickly on a common shaft and to cooperate with similarly shaped stationary stator wheels for producing a pumping effect. The rotor and stator wheels have rings of blades in which the blades are positioned at an angle to the plane of the wheel so that inclined channels are formed between the blades.

Various embodiments of rotor and stator wheels are known. In one embodiment the inclined channels are formed by milling the blades in a solid disc. In such an arrangement the channels and the vanes or blades which bound the channels have substantially the same dimensions, that is only half of the area of the ring of blades is passable in the axial direction. In another embodiment the wheels are formed from thin planar sheet metal sections by punching out the blades and turning the blades out of the plane of the sheet metal section. In this arrangement the ring of blades is passable over almost its full area due to the narrow thickness of the sheet metal section. Further, in another known embodiment the ring of blades is formed of individual blades or vanes inserted into and fixed in rings.

The characteristics of a turbo molecular pump are determined by its pumping speed and pressure ratio, that is the ratio of the pressures at its inlet and outlet. Both of these characteristics depend largely on the circumferential velocity of the ring of blades and, accordingly, on the velocity of the rotors. Consequently, the circumferential velocity and the rotational speed of the pump shaft are chosen as high as possible based on the strength properties of the rotor wheels.

For the above described types of rotor and stator wheels it is given that the stresses due to centrifugal force for rotors with milled blades result approximately half from the carrier body and half from the blades. Further, as compared to rotor wheels where the blades are formed from thin plate metal, the pumping speed of the milled blade type is smaller. However, in the sheet metal blade type of wheels the stresses resulting from centrifugal force are considerably higher, since with identical dimensions the additional loading of the carrier body by the centrifugal forces of the blades is approximately twice that in the wheels with the milled type of blade. As a consequence with identical dimensions the wheels with sheet metal blades have a total load which is 50 percent higher. If pumps using such wheels are operated at the permissible stress limit, the sheet metal blade type of wheel has to be driven at a proportionately lower rotational speed and, as a result, the advantage of its inherently higher suction capacity is partly lost. The third type of wheels described above is even more unfavorable with respect to its strength properties than is the sheet metal blade type of wheel.

Accordingly, the primary object of the present invention is to provide a rotor wheel for a turbo molecular pump which embodies the same or improved strength properties of the milled blade type of rotors, and at the same time has a high pumping speed similar to that of the sheet metal blade type of wheels. Therefore, in ac-

cordance with the present invention, a turbo molecular pump is provided having rotor and stator wheels formed of a carrier body with thin-walled blades of uniform thickness, and the acute angle included between the tangential plane at any given point on the surfaces of the blades spaced from the wheel axis and the plane of the wheel decreases as the distance of the given point increases from the wheel axis. Further, in such a wheel construction the following equation is satisfied:

$$a/\tan \alpha + d/\sin \alpha = 2 \pi r/z$$

wherein a is the dimension of the blades forming the ring in the axial direction of the wheel, d is the thickness dimension of the blades, r is the distance from the axis of the wheel to the given point on the surface of the blade, z is the number of blades in the ring of blades, and α is the acute angle formed between the tangential plane at the given point and the plane of the wheel.

By means of this rotor wheel construction, with the same dimension and at the same rotation speed, a considerable reduction is achieved in the centrifugal forces acting on the carrier body of the wheel, while the pumping speed is almost the same as that for the thin sheet metal blade type of wheels.

When the centrifugal forces for the milled blade type of rotor wheel described above are equal to 100 percent, the centrifugal forces for the thin sheet metal blade type of wheels as described above is about 150 percent while for the rotor wheels formed in accordance with the present invention the centrifugal force amounts to only about 60 percent. With these low stresses a corresponding increase in the circumferential velocity is allowed, though it should be noted that the stresses increase by the square of the circumferential velocity. Due to the increased circumferential velocity the pumping speed is similarly increased proportionately to the circumferential velocity, and, further, the pressure ratio increases in accordance with exponential function of the circumferential velocity. For achieving a certain pressure ratio of a turbo molecular pump it is possible to do so with a relatively lower number of pressure stages each of which consists of a rotor wheel and a stator wheel.

The various features of novelty which characterize the invention are pointed out with particularity in the claims annexed to and forming a part of this disclosure. For a better understanding of the invention, its operating advantages and specific objects attained by its use, reference should be had to the accompanying drawings and descriptive matter in which there are illustrated and described preferred embodiments of the invention.

FIG. 1 is a plan view of one embodiment of a rotor wheel or a stator wheel formed in accordance with the present invention;

FIG. 2a is a developed portion of the ring of blades in FIG. 1 taken along the line B-B;

FIG. 2b is a developed portion of the ring of blades shown in FIG. 1 taken along a line at a distance r from the axis of the wheel;

FIG. 2c is a developed portion of the ring of blades in FIG. 1 taken along the line A-A;

FIG. 3 is another embodiment of the rotor wheel in accordance with the present invention with the upper part of the view looking downwardly at the top of the wheel and the lower part showing the wheel in section;

FIG. 4 is a partial axially extending view of a turbo molecular pump embodying rotor wheels formed in accordance with the present invention, which wheels

have a construction similar to that shown in FIG. 3; and FIG. 5 is a view similar to FIG. 4 showing in detail a turbo molecular pump in which the rotor wheels, formed in accordance with the present invention, have a disc-shaped carrier body.

In FIG. 1 in the drawing, one embodiment of the rotor and stator wheels has an annular carrier body 1 with a plurality of blades 2 extending generally radially outwardly from the carrier body. As indicated in FIG. 2b, the blades have a thickness dimension d and the ring of blades has an axial dimension a . In FIG. 1 and 2b a point P is shown on one of the blades to locate it at a distance r from the axis M of the wheel, the tangential plane T formed at this point or any given point on the blades includes an acute angle α with the plane of the wheel. The angle α is dependent on the distance r of the given point from the wheel axis M. For any given point P on the blades 2, the following equation is satisfied:

$$a/\tan \alpha + d/\sin \alpha = 2 \pi r/z$$

wherein z is the number of blades in the ring of blades on the wheel.

In FIG. 3 another embodiment of a rotor wheel is shown formed in accordance with the present invention having an annular carrier body 12 with a T-Shaped cross-section with the head of the T-Shaped cross-section located radially inwardly so that the radially inner portion of the carrier body has a greater thickness or dimension in the axial direction than the blades forming the wheel in combination with the carrier body.

In FIG. 4 a portion of the axial length of a turbo molecular pump is shown containing both the stator and rotor wheels located within an annular shaped housing 6. The stator wheels are formed in accordance with the arrangement shown in FIG. 1 and the rotor wheels are formed in accordance with the arrangement as shown in FIG. 3. The annular carrier bodies 12 of the rotor wheels are fixed on a shaft 3 extending centrally through the housing 6. The rotor wheels and the shaft 3 combine to form the rotor of the turbo molecular pump. One stator wheel is located between each pair of rotor wheels and each stator wheel is held at its radially outer periphery by a ring 4 and spacer rings 5 positioned along the inner surface of the housing 6 hold the rings 4 of the stator wheels in position.

In FIG. 5 another arrangement of a turbo molecular pump is illustrated containing stator wheels formed in accordance with FIG. 1 and rotor wheels having a different form of carrier body. The carrier body of the rotor wheels is a solid disc 7. On one of the surfaces of the disc-shaped carrier body 7 which extends transversely of the axis of the pump a recess 8 is formed and on the opposite transverse surface a projection 9 is formed. The recesses 8 and projections 9 are shaped so that the projection of one carrier body fits into the recess on the adjacent carrier body so that the rotor wheels are aligned in a group. Each of the carrier bodies 7 contains a number of bores which are aligned with the bores in the other carrier bodies so that tension rods 10 extend through them for securing the individual rotor wheels together.

In accordance with the invention, the stator wheels are constructed in substantially the same manner as the rotor wheels, however, the carrier body 1 for the stator wheels does not have to be as strongly constructed as in the rotor wheels since no centrifugal forces are in-

volved. As indicated in FIGS. 4 and 5, the carrier body of the stator wheels has the same dimension in the axial direction as the blades forming the ring of blades about the carrier body. The rotor wheels constructed in accordance with the invention, as shown in FIGS. 1, 3 or 5, can be assembled with stator wheels also formed in accordance with the invention, as shown in FIG. 1, or the rotor wheels may be combined with conventional stator wheels in the assembly of a turbo molecular pump.

The embodiments of the invention in which an exclusive property or privilege is claimed are defined as follows:

1. Turbo molecular pump including rotor and stator wheels, each said wheel comprising a ring of blades with the blades positioned at an angle to the plane of said wheel, wherein the improvement comprises that at least one of said rotor and stator wheels includes a carrier body, a plurality of thin wall blades each having the same thickness and secured to and extending outwardly from said carrier body, said blade being shaped so that the acute angle formed between the tangential plane at any given point on the surface of each said blade and the plane of said wheel continuously decreases as the distance of the given point on said blade extends radially outwardly from the axis of said wheel, and the equation:

$$a/\tan \alpha + d/\sin \alpha = 2 \pi r/z$$

being satisfied for each given point on the surface of said blade, wherein a is the dimension of said blade in the axial direction of said wheel, d is the thickness dimension of said blades, r is the distance from the axis of said wheel to the given point on the surface of said blade, z is the number of said blades on said wheel, and α is the acute angle formed between the tangential plane at the given point and the plane of the wheel.

2. Turbo molecular pump, as set forth in claim 1, characterized in that said carrier body has an annular shape.

3. Turbo molecular pump, as set forth in claim 2, characterized in that at least a portion of said carrier body in the axial direction of said wheel has a larger dimension than said blades in the same axial direction.

4. Turbo molecular pump, as set forth in claim 3, characterized in that said carrier body is T-shaped in radial cross section and the head of its T-shaped section is located radially inwardly from the stem.

5. Turbo molecular pump, as set forth in claim 3, characterized in that said blades extend outwardly from the radially outer surface of said carrier body at a position thereon spaced axially from its axial end surfaces.

6. Turbo molecular pump, as set forth in claim 1, characterized in that carrier body has a solid disc-shape.

7. Turbo molecular pump, as set forth in claim 6, characterized in that at least a portion of said carrier body in the axial direction of said wheel has a larger dimension than said blades in the same axial direction.

8. Turbo molecular pump, as set forth in claim 7, characterized in that said blades extend radially outwardly from a radially outer surface of said carrier body at a position spaced axially from the axial end surfaces of said carrier body.

9. Turbo molecular pump, as set forth in claim 3, characterized in that an annular shaped housing extends in the axial direction of and encloses said wheels, an axially extending shaft positioned centrally within

said housing, a plurality of said rotor wheels having carrier bodies which in the axial direction of said wheel have a larger dimension for at least a portion thereof than the axial dimension of said blades and said rotor wheels mounted on said shaft, one said stator wheel positioned between each adjacent pair of said rotor wheels, and means for securing said stator wheels in said housing spaced radially outwardly from said shaft.

10. Turbo molecular pump, as set forth in claim 6, characterized in that an annular shaped housing extends in the axial direction of and encloses said wheels, a plurality of said rotor wheels each having solid disc-shaped carrier bodies are positioned within said housing, said disc-shaped carrier bodies each having a recess on one surface transverse to the axial direction and 15

a projection shaped to fit into the recess in another said carrier body in the oppositely disposed transverse surface so that said rotor wheels can be nested together within said housing, each said disc-shaped carrier body having bores formed therethrough with the bores in said carrier bodies being disposed in axial alignment, and rods extending through said bores for securing said rotor wheels together.

11. Turbo molecular pump, as set forth in claim 10, 10 characterized in that one said stator wheel being positioned between each pair of said rotor wheels in said housing, and said stator wheels being secured within said housing with the radially inner surfaces thereof being in spaced relationship from said rotor wheels.
